UNITED STATES PATENT OFFICE.

AUGUSTUS S. COOPER, OF SANTA BARBARA, CALIFORNIA.

PROCESS FOR UTILIZING RESIDUAL HEAT.

Application filed October 7, 1921. Serial No. 506,053.

To all whom it may concern:

Be it known that I, AUGUSTUS STEIGER COOPER, a citizen of the United States, residing at Santa Barbara, in the county of 5 Santa Barbara and State of California, have invented certain new and useful Improvements in Processes for Utilizing Residual Heat, of which the following is a specification.

10 The present invention relates to a process, and apparatus for using residual heat in laying asphaltic surfaces and has for its principal object to provide a process utilizing natural bituminized sand and the asphaltic residuum of petroleum stills.

Another important object of the invention is to provide an apparatus for imparting heat to the road-surface for receiving the bituminized sand or the asphaltic residuum.

20 In the drawing:—

Figure 1 is a top plan of a road in the process of being formed,

Figure 2 is an elevation thereof,

25 Figure 3 is a longitudinal section showing the apparatus for imparting heat to the road, and

Figure 4 is an end elevation thereof.

Referring to the drawing in detail it will be seen that the road foundation surfaced 30 with broken rock is indicated at H. A section of heated rock is placed on the foundation and is shown in Figures 1 and 2 ready to be covered with pieces of bituminized sand. The corrugated iron hoods A 35 for the oil flames are used in heating the broken rock. The hoods B¹ to B⁸ inclusive cover the heated rock and pieces of bituminized sand. The hoods B⁷ and B⁸ are used for a platform to place the bituminized sand 40 on the heated broken rock in section E. The heated and plastic pieces D of bituminized sand are ready to be raked and rolled after the hoods have been removed therefrom and will resemble the finished pavement rolled 45 and consolidated as is shown at C.

While section E is being covered with pieces of bituminized sand the space A is being heated; when the section E is covered with pieces of bituminized sand the heater 50 A is moved to F and the hoods B¹ and B² are carried forward and placed over the section E. This cycle of operation being constantly repeated.

A flat flame from an oil burner or burners is introduced in the hood A and is made 55 to impinge the surface of the graded or pre-

pared surface of the road. The oil flame heats the surface. After the heater moves forward, the bituminous sand rock broken in pieces that will go through a three inch 60 ring, is spread over the heated surface, thick enough so as to touch one another and at the same time covered with a hood or mantle B¹ to B⁸ that will withstand and confine the heat. The hood is allowed to remain until 65 the asphalt in the sand rock is softened by the heat retained in the surface of the road, so it can be easily raked. The bituminous sand rock will be kept plastic for a long time by the residual heat in the road surface 70 giving ample time for its manipulation. After the removal of the mantle the bituminous sand rock is raked to a uniform thickness over the surface of the road. After raking and while the bituminous rock is in 75 a spongy condition the surface is strewn with hot broken stone that will go through an inch and a half ring and not through an inch ring, sufficiently thick so that one piece of rock will nearly touch the adjoining piece. 80

Heating the surface and the broken rock removes the hydroscopic and other moisture, so that the asphalt will strongly adhere to them. A cold surface or rock chills the asphalt so that it will not enter the small pores 85 of the rock nor the spaces between them. After the broken rock is spread over the surface of the spongy bituminous rock it is consolidated by rolling. The pieces of broken rock are forced into the spongy sand 90 rock and the flat sides of the rock are turned upward by the action of the roller and form part of the surface of the completed road. The bituminized sand is forced upwards between the nearly adjoining pieces of broken 95 stone materially binding them together.

Referring especially to Figures 3 and 4 of the drawing it will be seen that I have illustrated an apparatus for imparting heat to the road bed which consists of the ironing 100 tank A which is open at both ends having a door 10 at one end and a door 11 at the other end which are hingedly mounted transversely of the ironing tank. A smoke chimney 12 is provided adjacent one end preferably the smaller end wherein is situated the door 10 and the ironing tank is adapted to be lifted by the apparatus 13 which may be of any preferred construction and is attached to a wheel vehicle indicated at 14. 110 It will be noted that the smaller end of the tank A is situated adjacent the vehicle so as

to follow the same and will be hereinafter known as the front end thereof. A compressed air pipe 15 is in communication with a suitable compressed air tank, not shown, 5 carried by the vehicle 14 and communicates with the burner 16 having the flat spout 17 so as to shoot a flat flame on the bottom of the tank A. This burner 16 is provided with a fuel pipe 18 leading from a suitable fuel 10 tank carried on the vehicle 14. This fuel will preferably be oil and it will be noted that a drip pipe 19 is in communication with the pipe 18 intermediate its ends so as to pass approximately centrally through the 15 top of the tank A so as to drop oil adjacent the spot where the flame from the spout 17 hits the bottom of the ironing tank A so as to keep this flame ignited and add intensive heat by having the flame extended and allowing the same to burn longer. The spout 17 is situated so as to pass through one of the openings 20 and if so desired there may be two of the burners.

Having thus described my invention what 25 I claim as new is:—

1. A process of the class described consisting of first heating the road surface, placing bituminized sand rock over the heated surface, covering the same with hoods 30 that will confine the heat, and allowing the hoods to remain in place until the asphalt in

the sand rock is softened by the heat retained in the surface of the road, raking the bituminous sand rock to a uniform thickness over the surface of the road, and when in a spongy condition strewing the surface with hot broken stone and afterwards rolling so as to form a smooth surface.

35

2. An apparatus for heating a road surface comprising an ironing tank including a bottom having a hood arranged thereover provided with openings in its front and rear end, closures hingedly associated with said openings so as to swing rearwardly, and means for raising the front end of the hood.

40

3. An apparatus for heating a road surface comprising an ironing tank including a bottom having a hood arranged thereover with openings in its front and rear end, doors hingedly mounted adjacent said openings so as to swing rearwardly of the tank, heating means for the bottom of the tank, and means for lifting the front end of the tank in the manner and for the purpose specified.

45

In testimony whereof I affix my signature in presence of two witnesses.

AUGUSTUS S. COOPER.

Witnesses:

CHARLES A. SLONKI,
CLIFTON C. NEUMAN.
